UNITED STATES PATENT OFFICE

LEO L. MILLER, OF FRANKFORT, INDIANA, ASSIGNOR TO McDougall COMPANY, OF
FRANKFORT, INDIANA, A CORPORATION

DESIGN FOR A KITCHEN CABINET

Application filed February 25, 1932. Serial No. 42,997. Term of patent 3½ years.

To all whom it may concern:

Be it known that I, LEO L. MILLER, a citizen of the United States, residing at Frankfort, in the county of Clinton and State of Indiana, have invented a new, original, and ornamental Design for a Kitchen Cabinet, of which the following is a specification, reference being had to the accompanying drawing, forming part thereof.

The figure is a front perspective view of a kitchen cabinet, showing my new design.

The fronts of the doors and the drawers of the cabinet have a different ornamental effect from the cabinet frame and so coact therewith that the doors are suggestive of "stretchers", the drawers are suggestive of "stringers" and the frame is suggestive of bonding material.

I claim:

The ornamental design for a kitchen cabinet, as shown and described.

LEO L. MILLER.
